UNITED STATES PATENT OFFICE.

CHARLES A. BAKER, OF WAUKESHA, WISCONSIN.

WHEELBARROW.

SPECIFICATION forming part of Letters Patent No. 740,214, dated September 29, 1903.

Application filed March 8, 1902. Serial No. 97,218. (No model.)

To all whom it may concern:

Be it known that I, CHARLES A. BAKER, a citizen of the United States, and a resident of the city and county of Waukesha, State of Wisconsin, have invented certain new and useful Improvements in Wheelbarrows, of which the following is a full, clear, and exact description.

This invention has for its object, first, to provide a simple, durable, and effective construction of wheelbarrow that should be characterized by great strength and durability, and, second, to provide a simple, cheap, and effective form of antifriction-bearing for wheelbarrows. These objects of invention I have accomplished by the novel features of construction hereinafter described, illustrated in the accompanying drawings, and particularly pointed out in the claims at the end of this specification.

Figure 1 is a view in side elevation of a wheelbarrow embodying my invention. Fig. 2 is an inverted plan view of the wheelbarrow. Fig. 3 is a view in cross-section on line 3 3 of Fig. 1. Fig. 4 is a view in cross-section on line 4 4 of Fig. 1. Fig. 5 is an enlarged view, partly in plan and partly in section, showing the wheel, its hub, and associated parts. Fig. 6 is a detail view in side elevation, showing one of the journal bars or brackets with a journal and roller and roller-bearings in position, the retaining-nut being omitted and the journal being shown in section.

The body A of the wheelbarrow is preferably formed of sheet metal, and this body has its bottom shaped to rest upon the supporting-bars B, that diverge from the front of the wheelbarrow and at their front are formed with the handles b. The supporting-bars B are formed from channel-iron or steel, (these terms being used synonymously herein,) and the handles or grips b are formed by bending together the edges of the supporting-bars, as clearly shown in Figs. 1 and 2 of the drawings, the supporting-bars B having their rear portions bent upward, so as to bring the grips or handles b in proper position to be readily grasped by the workman. The employment of channel-iron for the supporting-bars B is attended with many features of advantage over gas-piping or like supporting-

bars that have been heretofore used. In the first place, these channel-bars have the advantage of great strength and lightness, and, 55 in the second place, the channels of the supporting-bars serve to receive and hold against lateral movement the ends of the brace-bars and legs and channel-bars, as will hereinafter more fully appear. The legs C at the 60 rear of the wheelbarrow are each shown as V-shaped, and preferably these legs are formed from a single bar of metal that is bolted centrally, as at c, to the metal wheel of the wheelbarrow, while the upper ends 65 of the bar comprising the legs are bent inwardly and set within the channels B, as clearly shown in Fig. 4 of the drawings. The upper ends of the legs C are retained within the channels B by bolts c', and preferably 70 thimbles c² are placed upon these bolts in order to bring the nuts c³ in convenient position below the channels. By thus locating the bent upper ends of the legs C within the channels of the supporting-bars B a free firm 75 joint is secured between the legs and the supporting-bars, the outer side walls of the supporting-bars bracing the upper portions of the legs. While in the preferred form of the invention both of the supporting-legs C are 80 formed from a single metal bar, it is obvious that the employment of individual bars bolted to the body of the wheelbarrow and formed of the V shape shown would clearly fall within the scope of the invention.

To the lower portions of the outer members of the legs C are bolted, as at c⁴, the V-shaped brace-bars D, that extend longitudinally of the supporting-bars, as clearly seen in Figs. 1 and 2 of the drawings. As shown, these 90 brace-bars D are flat metal bars and their upper ends d are bent at quarter-turn and are set within the channels of the supporting-bars B, where they are retained by suitable bolts d'. Here again it will be seen that the 95 side walls of the supporting-bars effectively aid in retaining the brace-bars D against lateral movement. The bolt d' whereby the forward ends of the brace-bar are connected to the supporting-bars may also extend through 100 the body of the wheelbarrow, and thus aid in firmly securing it to the supporting-bars.

From the front converging ends of the supporting-bars B rises the front brace E, which

- in the preferred form of the invention consists of a single bar bent to W shape. The angular central portion and upper ends of the bar E are bolted, as at e, to the body of the 5 wheelbarrow, while the lower portions of the brace are connected by the bolts e' to the front ends of the supporting-bars B. This front brace E serves to give great strength, rigidity, and durability to the wheelbarrow.
- 10 Within the front open ends of the channeled supporting-bars B are set the journal bars or brackets F, that are connected to the supporting-bars by the bolt e' and preferably also by supplemental bolts e². (See Figs. 1 and 15 2.) Here again the advantage of forming the supporting-bars of channel-iron is apparent, since the side walls of the supporting-bars serve to effectively hold the journal bars or brackets F in position and against lateral 20 movement incident to the strains to which the wheelbarrow may be subjected. The front end of each of the journal bars or brackets F is flattened and formed with an eye f, that extends at an angle to the body of the bar F, so 25 that when the bars F are within the channels of the supporting-bars the opposing faces of the eyes f will be in parallel vertical planes. Through the eyes f of the journal-bars F extend the journals g of the wheel-hub G, and 30 around each of these journals and within the eyes f are placed a series of antifriction-rollers H. In the preferred form of the invention the hub G is a metal hub of considerably greater diameter than its journal g, and in 35 any event those parts of the hub G adjacent the inner ends of the journals g should be of sufficient size or should be provided with appropriate means for retaining the rollers H against inward displacement. As shown, the 40 outer ends of the journal g are screw-threaded, as at g', and the threaded portions of the journals are preferably somewhat smaller in diameter than the bodies of the journal g, so that the retaining-nuts K that encircle 45 the threaded portions of the journals when screwed to position will bear against the unthreaded shoulders of the journals at the inner ends of such threaded portions, as clearly shown in Fig. 5 of the drawings. When the 50 retaining-nuts K have been thus set in position, the extreme outer ends of the threaded portions of the journals g' will be upset, so as to securely retain the nuts K against accidental displacement. From the foregoing 55 description it will be seen that the journals g and the nuts K revolve with the hub G of the wheel and are relieved from friction by rollers H, that surround the journals.
- The wheel M is preferably a metal wheel, 60 and the spokes m of this wheel are preferably retained within sockets n, formed in the walls of the hub-plates N, as clearly shown in Figs. 1 and 5 of the drawings, the hub-plates N being preferably united by rivets n² 65 or in any other convenient manner. The hub-plates N are flanged, as shown, at their inner edges and encircle the hub G to se-

curely hold the wheel in place upon the hub. One advantage incident to my present invention is that the wheel and its hub may be 70 connected, as shown, with the journal bars or brackets, and these parts may thereafter be readily attached by unskilled labor to the supporting-bars of a wheelbarrow. In shipping this class of devices it is most convenient 75 to ship the parts in knockdown position; but inasmuch as it is necessary frequently for the assembling of the parts to be done by unskilled labor it will readily be seen that in this respect my present construction possesses features of material advantage, since when the wheel, its hub, and connected parts are sent from the factory the bearings are in readiness for use and need not be disturbed when attaching such parts to the supporting-bars of 80 85 the wheelbarrow.

It will readily be understood that the precise details of construction above set forth may be varied without departing from the spirit of the invention and that features of 90 the invention may be employed without its adoption as an entirety.

Having thus described my invention, what I claim as new, and desire to secure by Letters Patent, is—

95

1. In a wheelbarrow, the combination with the supporting and projecting side bars, of a hub journaled between the projecting ends of said bars, a wheel fixed to said hub, reduced journals upon the ends of said hub, eyes fixed 100 upon the projecting ends of said side bars, surrounding said journals and abutting against the ends of said hub, antifriction-rollers within said eyes and about said journals and abutments fixed to the outer ends of said journals 105 and extending over the outer ends of said rollers and the outer faces of said eyes, said rollers being held in place between the ends of said hub and said abutments.

2. A metal wheelbarrow, comprising the 110 converging, channeled, supporting-bars B, dish-shaped tray A formed of a single piece of sheet metal mounted on supporting-bars B, V-shaped legs C formed of a single piece of strap metal centrally bolted to said tray and 115 having its ends seated within and bolted to said channel-bars, single piece, V-shaped brace-bars D of strap metal having their lower, central portions bolted to said legs and having their ends seated within and bolted to 120 said channel-bars, a wheel M having a hub G provided with reduced journals g on its ends, journal bearing-bars F secured within and projecting forwardly from the ends of said channel-bars and provided with integral eyes 125 f bent at an angle to the body of said journal bearing-bars F and arranged parallel to each other, said eyes surrounding said journals and abutting against the ends of said hubs, reduced threaded portions g' on the ends 130 of said journals g and nuts K threaded upon the reduced ends of said journals, substantially as described.

3. In a wheelbarrow, the combination with

the supporting and projecting side bars, of a wheel and hub journaled between the projecting ends of said bars, reduced journals on the ends of said hub, eyes surrounding said journals and abutting against the ends of said hub, projecting supports for said eyes secured to the projecting ends of said bars, antifriction-rollers within said eyes and about said journals and means fixed to the outer ends of said journals for holding said rollers in place.

4. In a wheelbarrow, the combination with the converging hollow side bars, of a hub having a wheel fixed thereto journaled between the projecting ends of said bars, reduced journals formed on the ends of said hubs, eyes ar-

ranged in parallel relation surrounding said journals and abutting against the ends of said hubs, said eyes being provided with shanks extending laterally therefrom at an angle to the axis thereof and secured within the front 20 ends of said hollow side bars, antifriction-rollers within said eyes and about said journals, reduced threaded portions upon the ends of said journals and nuts upon said threaded portions and abutting against said eyes.
